UNITED STATES PATENT OFFICE.

RICHARD LOESSER AND ERNEST LOESSER, OF BROOKLYN, NEW YORK,
ASSIGNORS TO LEON DREYFUS, OF NEW YORK, N. Y.

DIAMOND-POLISHING TOOL.

SPECIFICATION forming part of Letters Patent No. 558,734, dated April 21, 1896.

Application filed July 1, 1895. Serial No. 554,537. (No model.)

To all whom it may concern:

Be it known that we, RICHARD LOESSER and ERNEST LOESSER, citizens of the United States, residing in Brooklyn, in the county of 5 Kings and State of New York, have invented certain new and useful Improvements in Diamond-Polishing Tools, of which the following is a specification.

This invention relates to an improved tool 10 for polishing the facets or other surfaces of diamonds, and is an improvement on the patent of Leon Dreyfus, No. 534,821, dated February 26, 1895.

The object of our improved tool is to provide means whereby the dop may be quickly 15 adjusted to the proper inclination of the facets, according to the grain of the diamond and according to the number of facets or other surfaces which are to be polished.

Our invention comprises a bed-piece or 20 base, a spring-bar fulcrumed near one end to the bed-piece and formed at its shorter portion with a head-plate having a circular opening formed with a guide-groove, a rotary ta-

ble mounted to turn in the opening of the 25 head-plate and provided with an annular flange received by the groove in the latter, said head-plate being split through so as to

form a tongue, which may be tightened up 30 by means of a set-screw, so as to bind the rotary table within the head-plate, an oscillating sleeve provided with opposite pivots or journals which bear in suitable lugs extending downwardly from the rotary table, said 35 oscillating sleeve being further provided with a tubular extension which passes through a slot formed in the rotary table, a split tube adapted to slide in the sleeve and its tubular extension, a dop-spindle on which the dop is

40 fixed for holding the diamond, said dop-spindle extending through the split tube, means for compressing and binding the lower split end of the latter onto the spindle, a split nut, the opening of which receives the upper end 45 of the split tube, a binding-screw for securing the split nut to the split tube, a fastening device, which extends from the split nut and passes through an arc-shaped slot formed in a guide-frame, which projects upwardly from

50 the rotary table, and means for axially adjusting the dop-spindle with its dop, all as

will be hereinafter described, and then particularly pointed out in the claims.

In the accompanying drawings, Figure 1 is a plan view of our improved diamond-polishing tool. Fig. 2 is a side elevation thereof, showing the same supported on the work-table, the polishing-wheel in dotted lines, and a second position of the dop-spindle, also in dotted lines. Fig. 3 is an enlarged longitudinal vertical section on line 3 3, Fig. 1, looking in the direction of the arrow, and the dop-spindle being shown in vertical position. Fig. 4 is an underside view of the outer portion or head-plate of the tool, showing the parts carried thereby. Fig. 5 is a detail side elevation of the setting wheel or cylinder for determining the number of facets to be produced or polished off, and of the parts which are adapted to be axially rotated in the setting-wheel, 70 the same view also showing an attachment which is adapted to extend under and steady the diamond and its mounting; and Fig. 6 is an enlarged transverse section on line 6 6, Fig. 5. 75

Similar letters of reference indicate corresponding parts.

Referring to the drawings, A indicates the bed-piece or base of the tool, which at one end is provided with a foot a, the under side of 80 which is rounded off, as shown. In the upper surface of the bed-piece is formed a longitudinal groove a', which receives the outer end of a flat metallic spring-bar B, which, near its outer end, is fulcrumed at b to the outer end 85 of the bed-piece, said spring-bar being formed at its outwardly-projecting end with a horizontal head-plate C. Adjusting devices are provided at the inner or tongue end of the spring-bar for a purpose to be hereinafter 90 stated, and the same consist of a screw-post d, projecting upwardly from the bed-piece through a smooth-walled opening in the spring-bar B and receiving a nut D, which forms an abutment or bearing for the spring- 95 bar when the plane of the head-plate C is adjusted by means of the adjusting-screw D', the stem of which passes through a screw-threaded opening in the spring-bar and into a screw-socket in the bed-piece. At one side 100 of the head-plate C the same is offset and split through at C', so as to form a tongue C², which

in connection with the portion of the head-plate opposite the same is provided with a screw-threaded bore to receive a clamping-screw E. The head-plate C is provided with 5 a circular opening and is formed with an annular groove C³ in its wall for receiving an annular flange f on a circular rotary table F, which turns in the opening in the head-plate. An oscillating sleeve G, provided with 10 opposite inclines g' g², is journaled by means of its opposite pivots or journals g in bearing-lugs f', projecting downwardly from the rotary table F, said oscillating sleeve being provided with an upwardly-extending tube G', which 15 passes through a slot F', formed in the rotary table F and extending transversely to the axial line of the pivots. Guided and arranged in the sleeve G and the tubular extension thereof is a tube h, which, as shown clearly in 20 Fig. 5, is longitudinally slitted in its lower part at h' and at each side of its slit is formed with ears h² h², which are provided with screw-threaded openings that receive a binding-screw H³ for the purpose of binding the split 25 part of the tube h onto the dop-spindle H, that passes through the tube, a spline h⁰ on the spindle, which is received in the slit h', positively preventing axial rotation of the spindle in the tube. A split nut I is provided with 30 an opening which receives the upper end of the tube h and which is clamped onto the tube by means of a binding-screw I', said split nut being provided with a laterally-projecting screw-pin J, which receives a clamping-nut 35 J'. In connection with the split nut I and the clamping-nut J' the tube h and spindle H of the dop are secured and guided in the sleeve G and its tubular extension by means of an upwardly-extending guide-plate K on the rotary table F, said guide-plate being arranged 40 parallel with and alongside of the slot F' in the table, and being also provided with an arc-shaped or curved guide-slot K', through which the screw-pin J on the split nut I passes. 45 The dop L is secured to the lower end of the dop-spindle H in any suitable manner for the purpose of holding the diamond L' in proper position. The lower end of the dop-spindle H is for that purpose preferably screw-threaded to receive a screw-threaded dop or 50 chuck l, which receives at its lower end opposing fastening or centering screws l', which fasten the mounting l² of the diamond L' in the socket of the dop or chuck. 55 Having thus described the construction of our improved diamond-polishing tool, we will now describe the method of operating the same.

A diamond having been secured in its dop, 60 which in turn is secured to the lower end of the dop-spindle H, the polishing off of the table, facets, and other parts of the same which have to be polished off can now be accomplished. If a facet is to be polished off, 65 (which, however, requires the inclined position of the spindle, as shown in full lines in Fig. 2,) the clamping-nut J' and the binding-

screw I' are loosened, the loosening of the latter permitting the rotation or turning of the tube h and screw-spindle H within the 70 tubular extension G' of the sleeve G, so that the proper disposition of the transverse plane of the facet or other part of the diamond to be polished in relation to the polishing-disk M may be secured. This axial adjustment 75 is accomplished by means of a setting-wheel N, which is adapted to turn within an enlarged opening in the oscillating sleeve G. The setting-wheel is made fast to the sleeve G in a manner to be hereinafter stated, and 80 when so made fast it permits the tube h to slide in it, an inwardly-projecting pin N' on the setting-wheel extending into the slit of the tube, so as to prevent relative axial movement the one to the other. The setting-wheel 85 N is provided, preferably, with three series of holes or sockets—namely, n n' n². The lower circular series of holes n preferably have arranged opposite to them a series of graduated numbers (not shown) which correspond to the 90 number of facets, and which holes n and their opposite numbers are adapted to register with an observation-hole g⁰ formed in the sleeve G. The upper circular series of holes or sprockets n² correspond in number and arrangement to the lower series of holes n and are adapted to receive the inner end of a set-screw P, which passes through the sleeve G, so that the setting-wheel, together with the diamond, may be secured in proper position 95 corresponding to the transverse plane of the same in relation to the plane of the polishing-disk. For properly setting or adjusting intermediate parts of the diamond to be polished "stars" the intermediate series of holes 100 n' is provided in the setting-wheel N, said holes being adapted to receive a set-screw P, which also passes through the oscillating sleeve G. After the dop-spindle and tube have been turned in the sleeve and its tube 105 extension and set in the manner described, the angle of inclination of the dop-spindle is fixed. This is done by rocking the oscillating sleeve G on its pivots and setting the clamping-nut J' against the guide-frame K, so that 110 the pin J will be opposite the graduation "45," for instance, or other graduation on the guide-plate K, which corresponds to the facets or other portion of the diamond to be polished off, the dop-spindle, in the present instance, 115 being shown in the proper angle of forty-five degrees for polishing off a facet.

In adjusting the inclination of the dop-spindle, as stated, a compound movement is produced—namely, the rocking movement of the 120 sleeve G on its pivots and the sliding of the tube h and dop-spindle in said sleeve and its tubular extension. This movement always causes the dop and diamond to be moved in a parallel plane to the polishing-wheel M.

The grain of diamonds varies in many instances, and as it is absolutely necessary for the purpose of properly polishing them that they be cut against their grain, the support-

ing rotary table F is provided, which, on being rotated, changes the position of the grain, with relation to the polishing-disk M, by moving the diamond to another point above the latter, after which the clamping-screw E is tightened, so as to bind the table within the head-plate C. If desired, a series of graduations may be provided on the under side of the head-plate C for determining the distance of rotation of the rotary table F, said table being provided with a suitable indicating-mark.

As a facet or other part of the diamond is ground down, the plane of the head-plate C with relation to that of the polishing-disk M changes, and this is compensated for by means of the adjusting-screw D', which is turned so as to act on the spring-bar B and thereby to cause the parallelism of the head-plate C and the rotary table F with the grinding-disk M. An adjustable limit pin or stop Q is provided with a screw-threaded portion, which is received in a screw-threaded opening in the bed-piece A, said limit-pin being further provided with a milled head q for the purpose of adjusting the same. This limit pin or stop Q, by abutting at its lower end upon the upper surface of the supporting-table T on which the tool is arranged, limits and determines the degree to which the facet, table, cullet, or other part of the diamond is to be polished, as, after the limit-pin abuts or rests upon the table T, the diamond is not pressed by means of the weight of the tool or the weight placed on the same against the polishing-surface of the polishing-disk M, and hence all further polishing thereof ceases. The form of the limit pin or stop is that of a micrometer-screw, but it is evident that any suitable form of stop may be substituted.

It may be found necessary to steady the diamond and its mounting in the chuck or dop L, and this may be effected from the side not being acted on by the polishing-disk by means of a steadyng-finger R, which at its lower end engages the diamond and at its upper end is secured by means of nuts r r' to a collar S, which is in turn secured to the upper part of the dop by means of a set-screw S', that takes into a groove l° in the dop, said groove permitting the adjustment of the finger by turning the collar and resetting-screw S' to any point around the diamond.

Having thus described our invention, we claim as new and desire to secure by Letters Patent—

1. In a diamond-polishing tool, the combination of a bed piece or base, a head-plate supported thereby and provided with an opening, an axially-rotatable dop-spindle pivotally supported in said opening, means for axially adjusting the dop-spindle, a movable arc-shaped guide-frame for the upper end of the dop-spindle, means for adjusting the dop-spindle on the guide-frame, as to its inclination, and means for rotating the guide-frame

in a horizontal plane, substantially as set forth.

2. In a diamond-polishing tool, the combination of a bed piece or base, a head-plate supported thereby and provided with a circular opening, a rotary table mounted to turn in said opening, and provided with a slot, an axially-rotatable dop-spindle pivotally supported in said slot, devices for adjusting the angle of the dop-spindle, means for axially adjusting the dop-spindle, and means for binding or fixing the table in the head-plate, substantially as set forth. 70

3. In a diamond-polishing tool, the combination of a bed-piece, a head-plate supported thereby, a sleeve pivoted below the head-plate and provided with a tubular extension, a dop-spindle provided with a dop and arranged within the sleeve and the tubular extension, a guide-frame projecting above the head-plate 85 and means for adjusting the spindle on the guide-frame, so as to determine the angle of inclination on the same, substantially as set forth. 80

4. In a diamond-polishing tool, the combination of a bed-piece, a head-plate supported thereby, a sleeve pivoted to the head-plate, a tube arranged and guided in the sleeve, a dop-spindle located in and adapted to be fixed to the tube, a guide-frame projecting above 95 the head-plate, and means for adjusting the spindle and tube on the guide-frame, substantially as set forth. 90

5. In a diamond-polishing tool, the combination of a bed-piece, a head-plate on the bed-piece provided with a circular opening, a rotary table mounted to turn in said opening, means for binding the table within the head-plate, an oscillating sleeve pivoted to the under side of the table and provided with a tubular extension passing through the slot in the table, a dop-spindle provided with a dop and arranged in the sleeve and the tubular extension and an upwardly-projecting guide-frame on the table provided with means for 110 adjusting the angle of inclination of the spindle, substantially as set forth. 100

6. In a diamond-polishing tool, the combination of a bed-piece, a spring-bar fulcrumed on the bed-piece and provided at one end with a head-plate and at the other end with adjusting devices for adjusting the plane of the head-plate, a dop-spindle provided with a dop, means for supporting the dop-spindle on the head-plate, and means for adjusting the position of the spindle, substantially as set forth. 115

7. In a diamond-polishing tool, the combination of a bed-piece, a spring-bar fulcrumed to the bed-piece and provided with a head-plate having a circular opening, adjusting devices passing through the spring-bar and into the bed-piece for adjusting the plane of the head-plate, a rotary table mounted to turn in the opening in the head-plate, means for binding or clamping the table in the head- 125 130

plate, an oscillating sleeve pivoted to the under side of the table, a spindle provided with a dop and arranged in the sleeve and extending through said slot, a guide-plate projecting from the table, and means for adjusting the angle of inclination of the dop-spindle with relation to the guide-plate, substantially as set forth.

8. In a diamond-polishing tool, the combination of a bed-piece, a head-plate projecting therefrom, a dop-spindle and dop, means for

supporting and adjusting the spindle in the head-plate, and a limit pin or stop, substantially as set forth.

In testimony that we claim the foregoing as our invention we have signed our names in presence of two subscribing witnesses.
